CIRCUIT BREAKER OPERATING SYSTEM

Albert Thibaudat, Paris, France, assignor to
Forges et Ateliers de Constructions Electriques
de Jeumont, Paris, France, a French body corporate

Application June 1, 1949, Serial No. 96,469
In France June 4, 1948

7 Claims. (Cl. 175—320)

1

The present invention, which relates to the practical construction of remote-controlled operating systems for electrical circuit-breakers, has for its general purpose to operate such apparatus with very low quantities of energy and to obtain high security as regards operation and the protection of the personnel concerned.

The invention is applicable to all types of circuit-breakers, and more particularly to a novel kind of apparatus of this class recently suggested but not itself forming the subject of the present invention.

Such apparatus comprise autonomous insulated operating mechanisms, exposed to the high tension of the line and consequently made normally inaccessible. They are provided with a source of mechanical energy, such as a tank of highly compressed air, and one or more auxiliary sources of control current, such as dry cells or storage batteries of suitable type. These sources of mechanical and electrical energy, as well as the mechanisms which are provided for operating each circuit-breaker pole separately or all the poles at once, are mounted on the high tension side, without any connection with the ground. The operating mechanisms are remote-controlled by radio apparatus, the receivers being associated with these mechanisms.

One of the main objects of the invention is to provide simple and effective means for controlling the circuit-breaker by these radio apparatus, in cases where the operating systems comprise a source of electrical controlling energy, as well as in cases where they do not comprise such a source.

Another object of the invention is to operate the circuit-breaker rapidly by the very low output energy of the radio receivers, by means of electrical, mechanical or pneumatic relays.

One of the objects of the invention is to obtain the rapid reclosing operation of the circuit-breakers controlled by a radio link or connection.

The invention has likewise for its objects to protect the sensitive members of such remote-controlled systems against shocks and vibrations, to allow the inspection and maintenance of these sensitive members without danger, to afford means for manual operation of the circuit-breakers, without having recourse to the remote-control, and to provide safety devices in conformity with the regulations prescribed for high-tension apparatus.

Other objects and advantages of the invention will hereinafter appear from the following

description given with reference to the accompanying drawings, in which:

Fig. 1 is a diagram representing a system of control by radio link, with two sources of operative energy and two sensitive control relays;

Fig. 2 is a diagram relating to an analogous system having no powerful sources of energy but utilizing mechanical relays controlled by two electrical relays;

10 Fig. 3 shows a modification of Fig. 2, having only a single electrical relay;

Fig. 4 represents the structural arrangement of the operating system; and

15 Figs. 5 and 6 represent a safety device therefor, Fig. 6 being a section of Fig. 5 on the line m—n.

Fig. 7 is a sectional view of a supplementary connection.

When the circuit-breaker, or each pole thereof, 20 comprises a source of electrical energy such as a storage battery which is constantly recharged, for example by a current transformer and rectifier unit, the operating system may be arranged in conformity with Fig. 1.

25 In that figure, there is shown a transmitter W for emitting the radio or Hertzian waves used for control, this transmitter being at ground potential and provided with a suitable system of antennae d. This apparatus cooperates with

30 a radio receiver R which picks up the Hertzian control waves by its antennae A, and which may be provided with a source B₂ of electrical energy, such as a battery of dry cells, for example. This receiver is arranged in the interior of the control device 7 represented in Fig. 4, where the apparatus W is shown at 8.

The apparatus R feeds by its output circuit M₁ a sensitive relay C for closing the circuit-breaker, and by its output circuit M₂ a sensitive relay D for tripping or opening the circuit-breaker. These two relays operate selectively according to the nature of the signal picked up by the antennae A.

35 The closing relay C which need not be capable of producing directly the closing of the circuit-breaker or of one pole thereof, acts upon an electro-magnetic valve device comprising an electro-magnet E and a valve V. This valve device has an inlet v₁ for compressed air, connected to a high-pressure tank PT and an outlet v₂ connected to a suitable pneumatic closing mechanism P shown diagrammatically in the closed position of the high-tension circuit X, the circuit-breaker being shown at Z. The circuit of the electro-magnet E is fed by a storage

battery B_1 which is charged by a suitable device, such as a current transformer, for example, associated with a rectifier unit T^1 ; Y is a conventional three-way valve mechanically operated by the piston P for controlling the air-inlet and outlet.

The tripping relay D causes the opening of one pole or of all the poles of the circuit-breaker by means of the intermediate electrical relay F which is energized by the same source B_1 . This intermediate relay acts upon a sensitive latching device of any suitable type, such as a toggle for example. As illustrated, this latching device takes the form of a pawl L which maintains the circuit-breaker in the closed position by holding a lever N in the position shown, this lever being suitably connected to the moving parts of the circuit-breaker and tending to turn in the direction of the arrow towards its open position under the effect of a spring S which is arranged for storing up energy upon the preceding closure of the circuit-breaker. Instead of controlling a mechanical latch, the device D may control a pneumatic device similar to the valve V .

These arrangements have the result of reducing to a minimum the power and the working time of the relays C and D , but they make it necessary to utilize a source of controlling power such as B_1 .

According to Fig. 2, it is possible to dispense with the battery B_1 and to utilize for the control only the weak source of current B_2 . In this case, sensitive low-power relays C and D , which are actuated by the receiver set R , control the operating mechanism or mechanisms of the circuit-breaker by the intermediary of mechanical relays with stored energy or pneumatic relays interposed.

The sensitive closing relay C actuates a sensitive latching device analogous to that of Fig. 1, but having stored mechanical energy. This latching device consists for example of a pawl L_1 which normally holds the bell-crank lever N_1 . It will be assumed that this lever N_1 has been brought to the position shown by the previous closure of the high-tension circuit X ; in the course of that preceding movement, the spring S_1 has been tensioned by the stop s_1 , thereby storing elastic energy. When the circuit-breaker Z is to be closed, the closing relay C is energized by the receiver R , it sets free that energy so that the bell-crank lever N_1 turns clockwise and strikes against the stem of a valve V_1 (analogous to the valve V in Fig. 1). This valve acts as a pneumatic relay to direct compressed air into the mechanism P to close the circuit-breaker.

With the circuit-breaker Z closed, as shown, the tripping or opening relay D controls a similar mechanical relay having like elements; its pawl L_2 sets free the lever N_2 , and its spring S_2 which has been tensioned by the stop s_2 in the course of the preceding opening of the circuit-breaker, so that the lever N_2 will strike the stem of another valve V_2 , provided for controlling the opening movement of the piston mechanism P of the circuit-breaker which is provided with conventional three-way valves Y_1 and Y_2 operated by the piston mechanism P for controlling the air inlet and outlet. Instead of striking upon a valve V_2 acting as a pneumatic relay, the lever L_2 may likewise strike upon a suitable mechanical locking device of the circuit-breaker, if the latter is of the type urged elastically towards its open position.

In the previous example, it has been assumed

that the levers N_1 and N_2 of the mechanical relays are brought into the latching and energy storing positions shown, directly by the respective previous movements of the circuit-breaker. It is obvious that these operations of preliminary tensioning of the mechanical relays may be effected by separate pneumatic pilot-motors.

In order to effect the automatic reclosing of the circuit-breaker, it may be preferable to provide instead of two separate sensitive relays energized selectively as stated above, a single sensitive relay adapted to act upon the closing and tripping mechanisms alternately, according to the position of the moving parts of the circuit-breaker. It will then suffice to maintain this single relay energized for the operations of the reclosing cycle to proceed automatically in proper sequence.

Such an arrangement is represented in Fig. 3, where the lever G is actuated by the circuit-breaker so as to occupy the position a when the breaker is closed and to occupy the position b when it is open. This lever displaces a sliding rod F_1 which in the position a represents tensions the spring S_2 and in the position b tensions the spring S_1 . These two springs act upon the operating lever N_3 which is held fast in the position shown by the double pawl L_3 , controlled by the single relay E_1 .

Assuming that the circuit-breaker is closed (position a), if the receiver R energizes the sensitive relay E_1 which lifts the pawl L_3 , the spring S_2 will rock the operating lever N_3 counter-clockwise, and the lower part of this lever will strike upon the stem of the valve V_2 provided for tripping the circuit-breaker. Towards the end of the opening movement of the breaker, the lever G will pass rapidly into the position b ; the lever N_3 will rock in the opposite direction and will strike upon the stem of the closing valve V_1 , and so on.

The valves V_1 and V_2 can be arranged and connected as described with reference to Fig. 2.

It suffices therefore to de-energize the relay E at a suitable moment, for example by stopping the emission of radio waves to the receiver R , in order to lock the circuit-breaker in the desired position, after which the operating lever N_3 will become latched in the intermediate position shown.

In Fig. 3, there is no representation of a source B_2 for feeding the receiver R . It has been supposed that in this case the apparatus R picks up beamed radiations having sufficient energy to energize the sensitive relay E without requiring amplification. It is known in the art of ultra-short waves that modern appliances allow of obtaining such a result. It is obvious, however, that the system shown in Fig. 3 may also include a source of current corresponding to B_2 in Figs. 1 and 2, and conversely that the systems of Figs. 1 and 2 can be worked without such source.

In Figs. 1 to 3, there are shown elements 16, 15 and 10 which allow for manual operation of the circuit-breaker to secure its opening, the element 10 being an insulating pillar which, in turning around its axis, causes its arm 15 to actuate the fork 16 and thereby the element L , L_2 or L_3 respectively, in order to effect the tripping of the circuit-breaker by setting free the energy provided for the purpose, as explained above. This manual operation of the breaker will be described more fully hereinafter with reference to Fig. 4.

The receiver apparatus R of Figs. 1 to 3 and

their accessories must be mounted in such a way as not to be exposed to shocks or vibrations which may be manifested in the course of the operation of the circuit-breaker and which may affect their normal working. Moreover, it is desirable to be able to inspect these apparatus and accessories from time to time in order to check their condition; these inspections must be possible under the prescribed conditions of safety such that the personnel is not exposed to any danger and that the service is not interrupted.

It is likewise necessary to be able to operate the circuit-breakers by hand, without having recourse to the remote control, and to comply with specified safety regulations.

Fig. 4 represents an arrangement which allows all these results to be obtained. In this figure, there is shown one pole of a high-tension circuit-breaker, constituted by a switch proper 1, of any suitable type, having external connections 2 and 3 and mounted upon a base 4; this latter is supported upon a platform 5, insulated in relation to the ground by means of suitable insulating pillars, represented diagrammatically by the chain lines 6.

The base 4 contains mechanism for operating the switch 1, as well as a source of energy for actuating that mechanism. As stated above, this source may be constituted for example by a tank of compressed air (not shown) provided with a valve which, when opened, effects the closing of the switch. A suitable member, constituted for example by a second valve or by a locking device is provided for effecting the tripping of the switch 1.

These members for closing and opening the circuit-breaker pole are likewise mounted in the interior of the base 4. They are actuated by a control device 7 which corresponds to the element R in Figs. 1 to 3, and comprises one or more receiver apparatus, sensitive to the action of Hertzian radiations, emitted by a suitable transmitter set 8 and directed in the line of the arrow 9. The control device 7 may also contain the relays C and D shown in the previous figures, as well as the current sources B₁ and B₂ with their accessories.

The device 7 is supported by a separate insulating pillar 10 which can not only turn around its longitudinal axis A—B when the lever 11 is manipulated, but also rock or pivot in a vertical plane around a hinge 12, so as to bring the control device 7 into its inoperative position designated by 7' and shown in broken lines.

The electrical connections between the control device 7 and the base 4 are effected by flexible leads 13 which terminate in contact members 14; these latter may take the form of plugs, contact springs or other devices arranged to establish the desired connections when the pillar 10 is in the vertical position shown.

The pillar 10 has likewise a mechanical connection with the base 4; this connection is represented in the form of a metallic arm 15 which engages in a movable fork 16.

Each pole of the circuit-breaker may have an over-current relay for causing its tripping in case of over-load or short-circuit. This relay, not shown, is disposed in the interior of the base 4 and acts directly upon the operating mechanism, being at the same high-tension potential.

The system represented in Fig. 4 can operate in the following manner:

The insulating pillar 10 being in the vertical position, the contact members 14 and the flexible wires 13 establish the necessary connections be-

tween the radio-receiver or receivers R disposed in the interior of the control device 7 and the closing and tripping members for the switch 1, which are mounted in the base 4, so that, according to the nature or the modulation of the wave directed along the arrow 9 by the emitter 8 onto the control device 7, the switch 1 is operated in the desired sense in the manner described above.

During the operation of the switch 1, shocks 10 and vibrations which may appear therein, are not transmitted to the control device 7, nor to the sensitive apparatus which it encloses, for they are supported, according to the invention, by a separate pillar. In order further not to transmit 15 the said shocks and vibrations by the arm 15, a sufficient clearance can be provided between that arm and the prongs of the fork 16.

In order to operate the switch 1 by hand, it suffices to actuate the lever 11 which is mounted 20 at a standard height in relation to the ground. By means of this lever, the pillar 10 can be turned around its longitudinal axis A—B; the arm 15 then shifts the fork 16 which is arranged to operate directly or indirectly the members for 25 closing or opening the switch 1, according to the direction of this shifting movement. The parts 15 and 16 may for example act upon the intermediate relay means, as shown in Figs. 1, 2 and 3. There is thus made available a simple means 30 for closing and opening the circuit-breaker, without having recourse to the remote control.

If it is desired to inspect without danger the apparatus of the control device 7 for adjustment or maintenance or again to effect for example 35 the recharging or the rapid replacement of a storage battery which the device 7 may contain, the pillar 10 is made to rock or pivot in the direction of the arrow 17, thereby bringing the lever 11 into the position 11' and the control device 7 into the position 7'. This has for effect 40 to interrupt the connections established by the contacts 14; these contacts move to the position 14', and the flexible wires to 13', so that the control device 7 is no longer under high-tension voltage and can be inspected without any danger.

At the moment of the separation of the contacts 14, there may be produced an interruption of capacitance currents, the break being liable to damage the apparatus, such as the sensitive 45 relays which form part of the control device 7. In order to obviate that drawback, it is possible to provide a supplementary connection 13—14 which is always interrupted last of all and which is connected not to those sensitive apparatus, but to the frame of the control device 7. As 50 shown in Fig. 7, the contact element 14 provided with a flexible shunt connection 13, is carried by a sliding rod 14A and held against the base 4 by a spring 14B. When the cabinet 7 is withdrawn, the moment of separation of the element 14A from the base 4 is fixed by a stop 14C located at such as distance that this supplementary connection will interrupt the capacitance currents.

When the pillar 10 is not in its normal position, 55 the possibilities of operating the switch 1 are limited to the action of the maximum-current relay disposed in the base 4. This relay can trip the circuit-breaker automatically in case of over-load or short-circuit, but it is not possible to operate the circuit-breaker in a non-automatic manner.

It is therefore necessary, before rocking or 60 tilting the pillar, either to open the respective pole of the circuit-breaker, or to transfer the protection of the circuit in question to other 75

apparatus; in the first case, it is also necessary to take the prescribed safety precautions such as the isolation of the circuits, and so on.

In order to compel the operator to take these preliminary measures of precaution automatically, recourse may be had to the following means:

By providing a device for blocking the hinge 12, the rocking or tilting of the pillar 10 is allowed only after a certain rotary motion around its longitudinal axis A—B; this rotation is such that it causes necessarily the opening of the circuit-breaker by the arm 15 and the fork 16. Such a mechanical block is readily produced for example according to Figs. 5 and 6.

As there shown, the insulating pillar 10 can rock or tilt around the pivotal shaft 12 (Fig. 5) which occupies normally the position $p-p$ marked in Fig. 6. The pillar is held fast by the plunger core 19 which normally engages in the extension 18 of the pillar 10. This extension comprises an inclined slot 21.

In order to be able to rock or tilt the pillar 10, there are two possibilities. The first consists in bringing the shaft 12 from the position $p-p$ to the position $p'-p'$; this corresponds to a rotation of the pillar around the vertical axis through an angle q (Fig. 6). Such rotation produces the tripping of the circuit-breaker by the effect of the members 15 and 16 (Fig. 4), as has been explained already. After such rotation of the pillar, the latter can be rocked or tilted around the axis $p'-p'$, the plunger core 19 escaping by way of the slot 21.

On the other hand, if the necessary steps have been taken to ensure the prescribed protection of the line pole or phase in question, for example by means of other circuit-breakers, the safety contacts 22, 22', etc. of the interlocking circuit 23 will be closed, the coil 20 then withdrawing downwards the core 19, and the operator can freely rock or tilt the pillar 10 without actuating the fork 16, that is to say, without tripping the switch 1.

What I claim is:

1. In a pneumatically operated high-tension circuit-breaker of the type controlled by a radio-receiver energizing sensitive magnetic relays, a remote control and emergency operating mechanism connected to the high tension, comprising a compressed-air container, an air-cylinder with a driving piston and air-valves interposed between said container and said cylinder, mechanical valve control relaying devices of spring type driven by said piston to store up control energy, tripping means for said relaying devices, formed by ratchets attached to the armatures of said sensitive magnetic relays, and a manually operated control device for emergency operation of the circuit-breaker, said device comprising a pivotally mounted and rotatable insulating pillar mounted adjacent to the circuit-breaker, an insulated control cabinet supported by said pillar, said cabinet accommodating the radio-receiver and those elements of said magnetic relays which require periodical attention, disengageable linking means between said pillar and said tripping means whereby the circuit-breaker can be operated by manual rotation of said pillar, and spring contact elements electrically connecting said sensitive relays inside said cabinet with co-operating control elements carried by the circuit-breaker, whereby pivotal movement of said pillar from its normal position disengages said linking means

and disconnects said cabinet from the high-tension.

2. In a pneumatically operated high-tension circuit-breaker of the type controlled by a radio-receiver energizing sensitive relays, an insulated mechanism for remote control and emergency operation by hand, comprising a compressed-air container, an air cylinder with a driving piston and control valves interposed between said container and said cylinder, mechanical valve-control relaying means of spring type driven by said piston to store up control energy, locking and tripping means, formed by pawls co-operating with said relaying means and driven by said sensitive relays, and an emergency control device for releasing said pawls manually, said device comprising an axially rotatable pillar pivotally mounted in an upright position adjacent to the circuit-breaker, an insulated control cabinet carried by the upper end of said pillar for accommodating the radio-receiver and those of the control elements which require periodical attention, disengageable linking means for tripping said pawls by rotation of said pillar, said disengageable linking means formed by a movable control fork upon said pawls and a co-operating control rod upon said pillar, and elastic contacts interconnecting said control elements carried by said pillar with the remaining control elements carried by the circuit-breaker itself, said linking means and contacts being disengaged upon pivotal movement of said pillar from its upright position towards an inoperative position.

3. In a circuit-breaking combination according to the claim 2, an additional elastic contact between the cabinet and the live parts of the circuit-breaker, said additional contact being independent of the sensitive control elements of the relaying means and having a longer stroke than the first-mentioned elastic contacts, whereby said additional contact separates last of all for interrupting capacitance currents.

4. In a circuit-breaker combination according to claim 2, safety means for preventing pivotal movement of the pillar towards its inoperative position until the circuit-breaker has been tripped, said safety means being formed by a locking device at the pivot of said pillar, said locking device comprising an extension upon said pillar, said extension including a slot, and a locking plunger core engaging in said slot, and said slot being inclined in such a direction that said pivotal movement can take place only after manual rotation of said pillar to produce the tripping of the circuit-breaker.

5. In a circuit-breaker combination according to claim 2, safety means for preventing pivotal movement of the pillar until the preliminary operations prescribed by safety regulations have been effected, said safety means comprising a safety circuit, a source of current for said circuit, a plurality of contacts in said circuit, said contacts being interlocked for closing said circuit when all the prescribed preliminary safety operations have been effected, a coil energized by said circuit when closed, and a plunger forming an armature of said coil adapted to lock the pivotal movement of said pillar when said coil is de-energized.

6. In a high-tension circuit-breaker of radio remote control type, having pneumatic operating mechanisms including a piston located at the high potential of said circuit-breaker, a radio receiver and intermediate relay means for controlling said operating mechanisms, said inter-

mediate relaying means being energizable by the output of said radio receiver, an entirely autonomous control mechanism comprising a low power closing relay and a low power tripping relay both energizable by output circuits of the radio receiver, two separate mechanical valve control relaying devices of spring type, each including a rotatable lever, the first driven by the closing movement of said piston to store up control energy and the second by the opening movement of the circuit-breaker, and separate sensitive retaining elements mechanically connected to the armatures of the corresponding low-power relays and arranged for normally locking said levers in their respective terminal positions, the energization of the corresponding relay causing one of said levers to be released, two air-valves for controlling the operation of said operating mechanisms, said valves being positioned to be operated by the respective levers when released, and a device for emergency actuation of said relaying means, said device comprising a pivotally mounted and axially rotatable pillar located in an upright position adjacent to the circuit-breaker, an insulated control cabinet carried by the upper end of said pillar for accommodating the control elements which are sensitive to shocks and vibration and require inspection, disengageable linking means for releasing the stored-up control energy of said spring elements by manual rotation of said pillar, said linking means being formed by a movable control fork carried by said mechanical relaying means and a co-operating control rod upon said rotatable pillar, and elastic contact elements interconnecting the sensitive control elements accommodated by said cabinet with control elements carried by the circuit-breaker, whereby the rocking of said pillar into inoperative position disengages said linking means and contact elements so that said cabinet can be safely inspected.

7. In a high-tension circuit-breaker of the radio remote control type, having pneumatic operating mechanisms located at the high potential of said circuit-breaker, a radio receiver and intermediate relaying means for controlling said operating mechanisms, said intermediate relaying means being energizable by the out-put of said radio receiver, an entirely autonomous control mechanism comprising a single low-power relay

connectible to the out-put of the radio receiver, and a two-way mechanical relaying device including a rotatable control lever, two spring elements for biasing said lever towards opposite end positions and for storing up mechanical energy during the closing and opening movements respectively of the circuit-breaker, a sensitive retaining element mechanically connected to the armature of said low-power relay for releasing said lever upon energization of said relay, two air-valves for controlling said operating mechanisms, said valves being positioned for operation by said lever in its opposite end positions respectively, and a device for emergency actuation of said relaying means, said device comprising a pivotally mounted and axially rotatable pillar located in an upright position adjacent to the circuit-breaker, an insulated control cabinet carried by the upper end of said pillar for accommodating the control elements of said relaying means which are sensitive to shocks and vibration and require inspection, disengageable linking means for releasing the stored-up mechanical energy of said spring elements by manual rotation of said pillar, said linking means being formed by a movable control fork carried by said mechanical relaying means and a co-operating control rod upon said rotatable pillar, and elastic contact elements interconnecting the sensitive control elements accommodated by said cabinet with control elements carried by the circuit-breaker, whereby the rocking of said pillar into inoperative position disengages said linking means and contact elements so that said cabinet can be safely inspected.

35 ALBERT THIBAUDAT.
